TILE

Kenneth E. Froberg, Plymouth Meeting, Pa., assignor to American Encaustic Tiling Company, Lansdale, Pa., a corporation of New York

Continuation of applications Ser. Nos. 56,367 and 56,369, June 16, 1959. This application Jan. 6, 1960, Ser. No.
58,947

Term of patent 14 years

(Cl. D18—2)

FIG. 2.

FIG.3.

Fig. 1 is a perspective view of a tile showing my new design;

Fig. 2 is a cross-sectional view taken on line 2—2 of Fig. 1; and

Fig. 3 is a front perspective view of a modified form of the tile shown in Fig. 1 and showing my same new design as shown in Fig. 1.

This application is a continuation of my copending applications, Serial Number D-56,367 and D-56,369, each filed June 16, 1959.

I claim:

The ornamental design for a tile, substantially as shown and described.
